UNITED STATES PATENT OFFICE.

PETER J. CHRISTMAN, JR., OF GREEN BAY, WISCONSIN, ASSIGNOR TO PAPER CONVERTING MACHINE CO., OF GREEN BAY, WISCONSIN.

INTERFOLDING MACHINE.

Application filed December 22, 1926. Serial No. 156,405.

This invention relates to interfolding machines and is particularly directed to a machine for interfolding sheets of paper, such as toilet paper, paper towelling, and the like.

5 Objects of this invention are to provide a novel form of interfolding machine which has a material reduction in the number of parts effective in forming the fold and securing the interfolding action, which avoids the necessity of using separately actuated and distinct members for holding the stack of interfolded sheets and for cooperating with the tucker blades, but which, instead, 10 is provided with a novel form of holder which has the double function of holding the interfolded sheets and at the same time, cooperating with the tucker blades to effect the folding of the sheets.

Further objects are to provide a machine 20 which will interfold paper sheets and hold them in their proper relation both during the actual folding and after the folding has taken place, so that the stack of interfolded sheets is prevented from separating and is 25 fed gradually from the machine without bulging or misplacement.

Further objects are to provide an interfolding machine which has an increased capacity as there are fewer parts to accelerate and retard in each cycle of operations and which has a single cam shaft and simpler lever mechanism for actuating both the tucker blades and the movable portion of the holder.

35 More specifically, this invention has for its further objects the provision of an interfolding machine in which a novel form of holder for the interfolded sheets is used, and in which the holder has one of its parts reciprocated back and forth across the line of feed of the paper, so that it cooperates with one of the tucker blades to form one of the folds, and moves out of the way of the other tucker blade to allow such latter tucker 45 blade to cooperate with the other member of the holder to form the other fold, and to so construct the holder that the necessity for presser flaps or similar separately actuated members is wholly avoided.

50 A further object is to provide a novel form of interfolding machine in which the major portion of the mechanism is located on one side of the machine, and in which the interfolded sheets are fed from the other unobstructed side of the machine.

An embodiment of the invention is shown in the accompanying drawings in which:

Figure 1 is a sectional view through the machine corresponding to a section on the line 1-1 of Figure 2;

60 Figure 2 is a fragmentary front view of the machine with parts broken away;

Figure 3 is a detail of a portion of the movable holder;

Figure 4 is a view drawn to an enlarged 65 scale showing the tucker blades, the holders, and the paper guide, with the parts in one position;

Figure 5 is a corresponding view showing the parts in another position.

70 Referring to the drawings, it will be seen that the machine comprises a pair of side frame members 1, one of which is indicated in Figures 1 and 2. These members carry a plurality of transverse shafts, hereinafter 75 described, and are braced by means of channel members 2 and 3, as shown most clearly in Figure 1. Approximately half of the machine has been illustrated in Figure 2, and it is to be understood that the machine 80 may be made as wide as desired.

The drive for the machine may be to the main shaft or cam shaft 4 which extends transversely across the machine. This shaft is geared to other shafts, as indicated generally in Figure 2, so as to impart the requisite speed of rotation to the several shafts. The cam shaft is provided with a cam 5 and with a cam 6 at opposite ends 85 which are, in turn, equipped with slots or cam grooves 7 and 8, in which the cam followers or rollers 9 and 10 of the tucker blade arms 11 and 12 ride. These tucker blade arms are pivoted, as indicated at 13, and are duplicated at opposite ends of the 90 machine. They carry tucker blades 14 and 15, respectively, and the cams are so constructed that the tucker blades are alternately moved inwardly towards the work.

95 The cam shaft 4 also carries a cam 16 (see Figure 2) which is similarly provided with a groove cooperating with the cam follower 17, such cam follower being carried by the upper end of a lever 18. The lever 18, as may be seen particularly from Figure 1, is carried by a bracket 19 bolted to the transverse bracing member 2. The lower end of the lever is slotted and connected by means of a bolt 20 with a link 21. The slot and bolt provide an adjustable connection so 100

that the throw of the link may be varied, as desired. This link extends to the rock arm 22 of a rock shaft 23. The rock shaft is provided with a pair of segmental gears 24 adjacent opposite ends thereof, and these gears mesh with racks 25 rigidly carried by the movable holder 26. This movable holder consists of a plate to which is bolted guiding bars 27, as may be seen particularly from Figure 3. These guiding bars 27 have the racks 25 bolted on their outer sides, and have plates 28 bolted on their inner sides. The plates 28 carry underhanging rollers 29 which, as may be seen from Figure 3, 10 operate with stationary guides 30 to prevent the plates 28 from inadvertently being lifted from the stationary guides. The stationary guides and the bars 27 are spaced by means of steel balls 31, such balls being carried in recesses in the bars 27 and in grooves in the stationary guides 30, as shown most clearly in Figure 1. The movable holder is provided with a lip or tongue 32 extending across its inner edge from one 20 end to the other, as shown in Figure 1.

A stationary holder 33 is mounted above the holder 26 and is spaced therefrom. This stationary holder is also provided with a lip or tongue 34 extending inwardly towards 30 the inwardly directed tongue 32 and also extending from one end of the upper holder to the other end thereof. This upper holder is bolted to the machine in any suitable manner, and may, if desired, be positioned 35 directly beneath a transverse brace 35 of the machine, as shown in Figure 1. The interfolded sheets are stacked or formed between the holders 26 and 33 in a manner herein-after described.

40 The machine carries a body roller 36 which constitutes the main roller of the machine. The paper is fed over a guiding roller 37 and passes between the main roller 36 and an auxiliary roller 38. The paper is held against the main roller 36 by means of an additional auxiliary roller 39 and passes beneath the cutter roll 40, such roll being provided with teeth cooperating with slots in the main roller in a well-known manner. 45 The main roller is grooved at suitable intervals and a series of stripping fingers 41 are positioned in the grooves, such fingers being carried by suitable rods 42 extending across the machine. The fingers continue downwardly and form guides 43 for the paper as it is stripped from the main roller after having been cut into the desired lengths.

50 Further, a second set of guiding fingers 44 are positioned adjacent the fingers 43 and spaced therefrom to permit the sheets of paper to pass between such fingers in an accurately guided manner. In order to assist the travel of the sheets of paper through the guides and from the main roller 55 after having been stripped therefrom by the

fingers 41, a plurality of endless belts 45 are provided and positioned with one stretch of the belts in alignment with the line of feed of the paper. These belts are carried by rollers 46 and 47, as shown in Figure 1. The paper is thus continuously fed to the main roller cut into suitable lengths and continuously stripped from the main roller and fed downwardly between the guides 43 and 44.

Attention is now directed to Figures 4 75 and 5 which show the position assumed by the parts during the interfolding operation. The paper is fed downwardly from the guides 43 and 44 and passes into the space between the stationary and movable holders 80 33 and 26, as shown in Figure 4, and is tucked by the upper tucker blade 15, the movable holder 26 moving outwardly into the position shown in Figure 4. Thus, the upper tucker blade 15 tucks the paper behind 85 the retaining lip 32 of the movable holder, as shown in Figure 4, while the next sheet is being fed into the fold of the paper. Thereafter, the upper tucker blade rises and the lower tucker blade 14 moves upwardly 90 and cooperates with the lip 34 of the stationary holder to form the upper fold in the paper. Prior to the arrival of the lower tucker blade 14, the movable holder 26 has moved outwardly out of the path of the 95 lower tucker blade, so that the parts occupy the position shown in Figure 5. The lower tucker blade is thus permitted to operate just inside of the lip 34 of the stationary holder and thus produces an upper fold in 100 the paper. This cycle of operation is repeated and the stack of interfolded paper is thus formed between the holders 26 and 33, such holder securely retaining the stack of interfolded sheets against displacement. Further, it is to be noted that the reciprocatory motion of the lower holder is also effective in securing a slight step by step outward feed of the stacked sheets.

110 It is to be particularly noted that the necessity for auxiliary rocking flaps or presser flaps and similar members of this type are wholly avoided by this invention, as the holders themselves perform not only their function as holders, but also perform the 11 function of a cooperative member for the tucker blades in effecting the folding and in holding the paper at the fold and for a material distance downwardly and upwardly 12 towards the center of the interfolded stack.

Further, it will be seen that the machine has been very greatly simplified as compared with prior interfolding machines, and that the number of moving parts has been very greatly reduced. The consequence is that the 12 machine is not only simpler to produce and easier to operate, but may be driven at a higher rate of speed than prior machines, as there are fewer parts to accelerate and decelerate during each cycle of operation.

It is to be noted further that the movable holder reciprocates from one side of the line of travel of the paper to the other side thereof. Further, it is to be noted that the major portion of the mechanism is located on one side of the machine and that the interfolded paper is fed from a substantially unobstructed portion of the machine.

Although the invention has been described in considerable detail, such invention is intended as illustrative rather than limiting, as the invention may be variously embodied and as the scope of such invention is to be determined as claimed.

15 I claim:

1. In an interfolding machine, the combination of means for successively feeding sheets of paper, a stationary holder, a movable holder adapted to receive between themselves the interfolded sheets, a tucker blade cooperating with the movable holder to form a fold, a second tucker blade cooperating with the stationary holder to form a second fold, and means for moving said movable holder out of way of said last mentioned tucker blade.

2. In an interfolding machine, the combination of means for successively feeding sheets, a movable and a stationary holder adapted to receive the interfolded sheets and each being provided with a lip, a pair of tucker blades adapted to fold and tuck the sheets from opposite sides behind said lips, and means for moving one of said holders out of the way of one of said tucker blades.

3. In an interfolding machine, the combination of means for successively folding sheets, a pair of holders adapted to receive between themselves the interfolded sheets, a pair of tucker blades adapted to form folds and tuck the sheets into position between said holders, said tucker blades and one of said holders being located on one side of the line of feed of said sheets, and means for moving the other of said holders back and forth across the said line of feed.

4. In an interfolding machine, the combination of means for successively feeding sheets, a pair of holders provided with lips and adapted to receive the interfolded sheets, a pair of tucker blades adapted to tuck the sheets back of said lips, said tucker blades and one of said holders being located on one side of the line of feed of said sheets, and means for reciprocating the other of said

holders back and forth across said line of feed.

5. In an interfolding machine the combination of means for feeding downwardly a succession of sheets, a pair of plates adapted to receive between themselves the interfolded sheets, each of said plates having an inwardly turned retaining lip and one of said plates being mounted for reciprocation across the line of feed of said sheets, a pair of tucker blades adapted to rock from opposite sides of said plates and tuck the sheets between said plates, said tucker blades cooperating with said lips to form folds, and means for causing the reciprocally mounted plate to move back and forth across the line of feed of said sheets and to thus move out of the way of the tucker blade cooperating with the other plate.

6. In an interfolding machine, the combination of means for successively feeding sheets, an upper holder and a lower reciprocating holder adapted to receive the interfolded sheets with such interfolded sheets resting upon the lower holder, each of said holders having inwardly directed lips of a width jointly approximating the width of the interfolded sheets, a pair of tucker blades adapted to tuck the sheets into the space between said holders, means for reciprocating the lower of said holders and causing its lip to pass into positions in front of and behind the lip of the upper holder, whereby the interfolded sheets are fed outwardly in a step by step manner.

7. In an interfolding machine, the combination of a pair of holders having inwardly directed marginal lips, means for successively feeding sheets downwardly towards said holders, an upper and a lower tucker blade adapted to tuck the sheets into the space between said holders, said holders acting as supports for the interfolded sheets, and means for causing relative motion between said tucker blades and said holders in timed relation, whereby the upper tucker blade passes downwardly between said lips and the lower tucker blade passes upwardly between said lips.

In testimony that I claim the foregoing I have hereunto set my hand at Green Bay, in the county of Brown and State of Wisconsin.

PETER J. CHRISTMAN, JR.
